CLAIM

The ornamental design for a glass reflector, as shown and described.

DESCRIPTION

FIG. 1 is a front elevation view of a glass reflector showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a first top, right, front perspective view thereof; and,

FIG. 8 is a second top, right, front perspective view thereof. The broken line showing in FIG. 8 is for the purpose of illustrating environmental structure and forms no part of the claimed design.

1 Claim, 8 Drawing Sheets
